COMBINED CATAMENIAL APPLIANCE AND GARMENT

Ethel C. Brown, Mission, Kans.

Application August 2, 1951, Serial No. 239,974

4 Claims. (Cl. 128—289)

1

This invention relates to wearing apparel and has to do more particularly with an improved undergarment that is adaptable for use as a catamenial appliance, the primary object being to provide simplified structure including a pocketed portion for receiving a sanitary pad or other absorptive.

It is the most important object of the present invention to provide a catamenial appliance and garment that includes a rather narrow, elastic, continuous body encircling band, together with a substantially semi-circular panel joined at the ends thereof to the band at diametrically opposed points on the latter, the panel having a strip thereon formed and mounted to present a pad-receiving pocket.

Another object of this invention is to provide a garment as above set forth wherein the aforesaid strip is longitudinally slotted to expose the pad held thereby, the strip having a width substantially the same as the width of the panel upon which the same is mounted.

Other objects include the way in which the strip is secured to the panel at the bight of the latter solely at the periphery of the strip; the way in which elastic means, secured to the strip only, adjacent the slot thereof, surrounds the latter and aids in holding the pad in place; and many more minor objects including simplified construction, all of which will be made clear or become apparent as the following specification progresses, reference being had to the accompanying drawing, wherein:

Figure 1 is a perspective view of a combined catamenial appliance and garment made pursuant to the present invention.

Fig. 2 is an enlarged, cross-sectional view taken on line II—II of Fig. 1.

Fig. 3 is a cross-sectional view taken on line III—III of Fig. 2; and

Fig. 4 is a transverse, cross-sectional view taken on line II—II of Fig. 1.

Fig. 3 is a cross-sectional view taken on line III—III of Fig. 2; and

Fig. 4 is a transverse, cross-sectional view taken on line IV—IV of Fig. 3 still further enlarged.

As above indicated, one of the most important features of the present invention is to provide a garment that is provided with means adapting the same to support a sanitary pad, which means does not adversely affect the device for use as a garment from the standpoint of discomfort or unsightly appearance of outer garments.

2

As will hereinafter appear, the entire appliance is extremely simple and therefore, easy and inexpensive to manufacture.

As illustrated in Fig. 1 of the drawing, the appliance comprises essentially but three component parts, namely, a continuous band 10, a substantially semi-circular, one-piece, seamless panel 12, and an elongated strip 14. The relatively narrow, lightweight band 10 is adapted to encircle the body of the wearer and is therefore, preferably made from elastic material. The panel 12 is also preferably flexible and may be made from any suitable fabric, the ends of the strap 12 being permanently secured to the band 10 at diametrically opposed points on the latter.

As is clearly shown by the drawing, the panel 12 is appreciably wider than the band 10 but is restricted at the bight thereof to substantially the width of a sanitary pad 16 to be used with the garment, presenting a relatively narrow, elongated strap 17. Panel 12 constitutes preferably, a sheet of material of single thickness, formed to present a pair of substantially triangular-shaped end portions 18 having their bases secured to band 10 and their apexes merging into strap 17.

The elongated strip 14 has substantially the same width as the width of the strap 17 and is secured to the latter on the normally uppermost face thereof solely by means of a continuous line of stitching 20 at the outermost periphery of the strip 14. Strip 14 is likewise preferably formed from a suitable fabric and in order to assure that the same maintains the shape illustrated by Figs. 1 and 2 of the drawing, strip 14 should be cut on the bias.

An elongated, longitudinally extending slot 22 is formed in the strip 14 to expose the pad 16 when the latter is placed in the pocket that is presented by the strip 14 and the underlying strap 17, the outermost limits of such pocket being defined by the line of stitching 20. Strip 14 is reinforced adjacent the slot 22 and the pad 16 is held properly in place within the pocket and upon the uppermost face of strap 17 by continuous, elastic means 24, preferably elastic thread, that is mounted in place next adjacent the slot 22 and in complete surround relationship thereto. Accordingly, the elongated, elliptical band-like strip 14 overlies the marginal edge of the pad 16 and by virtue of the elasticity of thread 24, pad 16 is slightly compressed at its marginal edge and held tightly against the uppermost face of strap 17.

It can well be appreciated that when the device is used as a catamenial appliance, little discomfort to the wearer is presented and the pad 16 is properly held in the necessary position to receive menstrual discharge, band 10 and strap 12 cooperating in holding pad 16 against displacement while permitting freedom of movement on the part of the wearer. Furthermore, the elastic thread 24 will readily permit removal of pads 16 and replacement thereof and the entire garment may be easily and quickly laundered.

Additionally, it can now well be appreciated that the device is adaptable for use as a garment without the presence of pad 16 since there are provided no uncomfortable parts such as metal-like fasteners and the like as is common in appliances of this character.

Forming of the garment from but three primary parts, i. e. band 10, panel 12 and strip 14 is of extreme importance to comfort, lightness of weight, ease and inexpensiveness of manufacture and utility, both as a garment and as a catamenial appliance. The single strap 17 with the small strip 14 thereon offers no discomfort whatsoever to the wearer when worn as a garment and a minimum of bulkiness when pad 16 is used.

The form of panel 12, so far as end portions 18 is concerned, is also important. They serve to hold strap 17 in place within the crotch; aid in holding pad 16 against displacement, present a protection to the wearer by virtue of their body-covering functions; add to comfort by lying flatly against the body; eliminate unsightly bulkiness that would otherwise show through outer garments; and present a covering, permitting the use of light-weight wearing apparel thereover.

While precise details of construction as above set forth may be varied, it is manifest that such changes as fairly come within the spirit of the invention as defined by the scope of the appended claims, are contemplated hereby.

Having thus described the invention what is claimed as new and desired to be secured by Letters Patent is:

1. A combined catamenial appliance and garment comprising a continuous, body-encircling, elastic band; a substantially semi-circular, flexible panel depending from the band and having the ends thereof joined to the band at diametrically opposed points thereon; and an elongated, longitudinally-slotted, flexible strip on the uppermost face of the panel at the bight of the latter and secured to the panel solely at the periphery of the strip to present a pad-receiving

pocket between the panel and the strip, the widths of the strip and of the panel being substantially the same at the strip.

2. A combined catamenial appliance and garment comprising a continuous, body-encircling, elastic band; a substantially semi-circular, flexible panel depending from the band and having the ends thereof joined to the band at diametrically opposed points thereon; an elongated, longitudinally-slotted, flexible strip on the uppermost face of the panel at the bight of the latter and secured to the panel solely at the periphery of the strip to present a pad-receiving pocket between the panel and the strip, the widths of the strip and of the panel being substantially the same at the strip; and continuous, elastic means secured to the strip adjacent the slot thereof and in surrounding relationship thereto.

3. A combined catamenial appliance and garment comprising a continuous, body-encircling, elastic band; a substantially semi-circular, flexible panel depending from the band and having the ends thereof joined to the band at diametrically opposed points thereon; and an elongated, longitudinally-slotted fabric strip on the uppermost face of the panel at the bight of the latter and secured to the panel solely at the periphery of the strip to present a pad-receiving pocket between the panel and the strip, the widths of the strip and of the panel being substantially the same, said strip being cut on the bias.

4. A combined catamenial appliance and garment comprising a continuous, body-encircling, elastic band; a substantially semi-circular, flexible panel depending from the band and having the ends thereof joined to the band at diametrically opposed points thereon; and an elongated, longitudinally-slotted, flexible strip on the uppermost face of the panel at the bight of the latter and secured to the panel solely at the periphery of the strip to present a pad-receiving pocket between the panel and the strip, the widths of the strip and of the panel being substantially the same at the strip, said panel including a pair of substantially triangular-shaped portions at the ends thereof and a relatively narrow, elongated strap joining the portions at the apexes thereof, the bases of the portions being secured to the band, the strap forming the said bight of the panel.
